UNITED STATES PATENT OFFICE

2,537,698

WATER-TUBE BOILER

Louis J. Peters, Laurelton, N. J.

Application April 10, 1946, Serial No. 661,144

1. Claim. (Cl. 122—235)

1.

This invention relates to an improved horizontal water-tube boiler especially adapted for use as a locomotive boiler but capable of use as a stationary boiler.

The primary object of the present invention is to provide an improved boiler of the above kind which provides maximum heating efficiency with minimum fuel consumption, and which eliminates the use of water and steam drums.

A more specific object of the invention is to provide an improved boiler of the above kind embodying water-filled transverse combustion chamber sections, each comprising a hollow frame having top and bottom members connected by spaced water tubes arranged in the path of the hot products of combustion passing from the fire box to the smoke flue.

A further object of the invention is to provide a boiler of the above kind which includes a fire box having water-filled front and side walls, water-filled transverse combustion chamber sections secured in assembled relation to the fire box and each comprising a hollow frame having top and bottom members connected by spaced water tubes arranged in the path of the hot products of combustion passing from the fire box to the smoke flue, and a steam receiver comprising a plurality of superposed intercommunicating hollow plate sections horizontally disposed above and communicating with the tops of the fire box walls and at least rearmost ones of the combustion chamber sections to receive steam therefrom.

More specific objects of the invention are to facilitate assembling and alignment of the combustion chamber sections, and to so construct and space the combustion chamber sections as to facilitate removal of soot therefrom.

The exact nature of the present invention, as well as other objects and features thereof, will become apparent from the following description when considered in connection with the accompanying drawings, in which:

Figure 1 is a view, partly in side elevation and partly in longitudinal section, of a boiler constructed in accordance with the present invention;

Figure 2 is a fragmentary horizontal section through the boiler of Figure 1, and taken substantially on the plane of line 2—2 of the latter figure;

Figure 3 is a fragmentary vertical longitudinal section taken on line 3—3 of Figure 2, with the casing of the boiler omitted;

Figure 4 is an elevational view of one of the

2.

combustion chamber sections forming part of the boiler shown in Figure 1;

Figure 5 is a fragmentary section through adjacent combustion-chamber sections taken on the plane of line 5—5 of Figure 4;

Figure 6 is a fragmentary section taken on line 6—6 of Figure 4;

Figure 7 is an enlarged section through one of the combustion-chamber sections, taken on line 7—7 of Figure 1;

Figure 8 is a horizontal section through the upper portions of a plurality of the combustion-chamber sections, taken on line 8—8 of Figure 1;

Figure 9 is a horizontal section through a modified form of combustion-chamber section;

Referring in detail to the drawings, the present boiler includes water-filled front and side fire box walls 5 and 6 respectively. The front wall 5 comprises a hollow-plate section having an opening 7 for introduction of fuel and closed by a suitable door 8. Each side wall 6 comprises a hollow frame which, in the form of Figure 1, includes side members 9 and 10, top and bottom members 11 and 12, respectively, and spaced straight water tubes 13 connecting and communicating with the top and bottom members 11 and 12. In practice, the top and bottom members 11 and 12 are connected by the water tubes 13, after which the side members 9 and 10 are assembled and welded to the top and bottom members 11 and 12. In this embodiment, the rear side members 10 have rearwardly inclined rear edges as indicated at 14. Any suitable form of grate of any well known or preferred type may be suitably installed in the fire box on a plane below the bottom of the fuel opening 7, and suitable provision will be made for disposition of ashes, depending upon whether the boiler is used as a stationary one or as a locomotive boiler.

Disposed behind the fire box within the combustion chamber of the boiler are a plurality of water-filled transverse combustion-chamber sections 15. These combustion-chamber sections are water-filled and, in this embodiment, each comprises a hollow frame embodying side members 16 and 17, top and bottom members 18 and 19, respectively, and a plurality of spaced straight water tubes communicating with and connecting the top and bottom members 18 and 19 between the side members 16 and 17 and arranged in the path of products of combustion passing from the fire box to the smoke flue 21. The frames of the combustion-chamber sections 15 are connected in series as at 22 so as to communicate with each

other near the top alternately near opposite sides thereof or in different vertical planes and to provide for efficient water circulation through all of the combustion chamber sections. As shown, the combustion chamber sections are disposed with the tops thereof substantially in the same plane as the top of the fire box, but the walls of the fire box extend below the bottoms of the combustion chamber sections. In this embodiment, the combustion chamber sections 15 are inclined rearwardly similarly to the inclination of the rear edges 14 of the side walls of the fire box. This arrangement provides for use of a maximum number of combustion chamber sections without unduly restricting the passage of products of combustion to the stack 21.

In order to facilitate cleaning of soot from the combustion chamber sections 15, they are preferably disposed in slightly spaced relation. In order to effect this spacing of the sections 15, each is provided at its lower portion with vertically spaced lugs 23 contacting the next adjacent section. Alignment of the sections is facilitated by providing each with small recesses or indentations 24 for reception of the free ends of the spacing lugs 23 as shown more clearly in Figures 4 and 5. This also prevents relative vertical or lateral displacement of the combustion chamber sections while spacing them. In order to facilitate cleaning of the combustion chamber sections, as regards accumulation of sediment therein, each is provided with a clean out opening at the bottom of each side member 16 and 17, closed by a plug 25.

The boiler further includes a steam receiver comprising a plurality of superposed hollow plate sections 26 connected to intercommunicate with each other as at 27 and thereby slightly spaced apart. The lowermost steam receiving section 26 is shown as relatively short so as to merely overlie the fire box, and this section is connected at 28 to the tops of the fire box walls to communicate with the latter and receive steam therefrom. The remaining sections 26 extend the full length of the fire box and the combustion chamber sections, the lowermost one of these longer sections being connected to at least rearmost ones of the combustion chamber sections as at 29 to communicate with the tops of the latter and to receive steam therefrom. The uppermost section 26 has a steam outlet pipe 30, and the sections 26 are provided with openings similar to the construction of steam radiator sections to facilitate the circulation of products of combustion therethrough and thereby insure production of high steam pressure.

Means which is yieldable longitudinally of the boiler is provided to tie the fire box and the combustion chamber sections together so as to compensate for expansion and contraction thereof. This means preferably consists of horizontal tie rods 31 extended longitudinally of the boiler at opposite sides of the fire box and the combustion chamber sections and passing through cross bars 32 extended across the front wall 5 of the fire box above and below the door 8 and across the upper and lower portions of the rearmost combustion chamber section 15, compression springs 33 being provided on corresponding projecting ends of the rods 31 between the adjacent cross bars 32 and nuts 34 adjustably threaded on said projecting ends of rods 31 outwardly of the bars 32. By adjusting the nuts 34, the compression of the springs 33 may be regulated so that the fire box and the combus-

tion chamber sections will be maintained in proper assembled relation at all times.

The fire box and the combustion chamber sections are suitably encased, such as by a metallic shell 35 having a refractory lining 36, the door 8 being carried by the shell 35 and located within an opening of the latter aligned with the fuel opening 7.

In operation, the hot products of combustion from the fire box heat the water in the fire box walls and the water tubes thereof, generating steam which passes to the steam receiver. These hot products of combustion also flow rearwardly through the combustion chamber sections, circulating about the frame members and water tubes thereof so as to generate additional steam that is supplied to the steam receiver. As the water is heated in the fire box walls and in the combustion chamber sections, effective circulation of the water takes place as indicated by arrows, facilitating the steam generating operation. Maximum heating of the water is obtained before the products of combustion pass to the stack 21, and the steam is additionally heated in the sections of the steam receiver to insure production of high pressure steam, the products of combustion being allowed to pass upwardly from between the combustion chamber sections for circulation about the steam receiver sections.

As shown in Figure 9, the capacity of the side walls of the fire box and of the combustion chamber sections may be increased by providing a greater number of water tubes. In other words, in the constructions thus far described, the water tubes 13 and 20 are arranged in a single row, whereas the water tubes 20a of Figure 9 are arranged in two rows with the tubes of one row staggered with respect to those of the other row. This arrangement provides for an increased number of water tubes without increasing the thickness of the section or wall.

Of course, the usual facilities will have to be provided for cleaning or blowing soot from the water tubes as is generally well known in the art.

From the foregoing description, it is believed that the construction, operation and advantages of the present invention will be readily understood and appreciated by those skilled in the art. Other modifications and minor changes in details of construction are contemplated such as fall within the scope of the invention as claimed.

66 What I claim is:

In a water tube boiler, a water filled front fire box wall embodying a hollow rectangular plate having a fuel feed opening therethrough, water filled side walls each comprising a rigid rectangular frame composed of hollow front, rear, top and bottom members, and spaced straight water tubes connecting said top and bottom members within the frame, the rear members of said side walls having rearwardly inclined rear edges, a plurality of spaced water filled transverse combustion chamber sections disposed at a rearward inclination behind the side fire box walls and each comprising a rigid rectangular frame composed of hollow side top and bottom members, and spaced straight water tubes connecting said top and bottom members within the frame, nipples connecting the frames of said transverse sections in series near the top and alternately near opposite sides thereof, the frame of each transverse section having spacing lugs and re-

cesses arranged so that the lugs of each section seat in the recesses of a next adjacent section to space and prevent relative vertical or lateral displacement of said transverse sections, a steam receiver comprising a plurality of spaced superposed hollow plate sections overlying the fire box and the transverse sections, and nipples connecting said plate sections to each other and to the tops of the fire box walls and to the tops of rear ones of the transverse sections.

LOUIS J. PETERS.
